UNITED STATES PATENT OFFICE

ALBERT BREISIG, OF VIENNA, AUSTRIA.

APPARATUS FOR PRODUCING GAS AND COKE IN ALTERNATELY-WORKING WATER-GAS GENERATORS.

Application filed May 4, 1926, Serial No. 106,742, and in Austria May 7, 1925.

The invention relates to an apparatus for producing gas and coke as a by-product, especially water gas or a mixture of water gas and coal (distillation) gas by means of 5 a generator, in the operation of which the so-called blowing periods are alternating with the gasifying periods.

The invention consists of a special construction of the generator, owing to which 10 the removal of the coke can very easily be effected without interfering with the generation of the gas.

The consideration on which the invention 15 is based was the following: Coke which is in the form of pieces and not caked together, on being deposited, that is to say on settling freely itself, has the tendency of forming heaps the sides of which have a certain inclination or gradient of slope, the angle of 20 this slope depending upon the friction coefficient (co-factor) of the pieces of coke. The pieces lying in the plane of the slope are in a state of unstable equilibrium and very weak forces are sufficient for causing 25 these pieces to roll downward, for instance gas or air flowing along the slope or through the material. If such forces act continuously, the pieces of coke will roll down until the material is heaped at an angle or slope 30 smaller than the said natural angle. As soon as the material has acquired the new equilibrium the action of the gases sweeping along the coke will not be sufficient any more for initiating the rolling movement of the 35 pieces.

In accordance with the present invention 40 the generator is made so that the power of the air draught employed in the usual operation of such generators or that of the blow 45 gas produced in the apparatus can be utilized for removing the coke in the described manner. For this purpose on the point where the coke is to be removed from the generator, the possibility must be given to 50 the coke of forming a slope. This is attained by enlarging the cross-section of the generator at the said place. Such an enlargement on the junction between the distillation chamber on the one hand and of 55 the gasifying or coke chamber on the other hand exists already in most of the generators producing the mixture of gas above indicated. From the space of the said junction transversal channels for the escaping 60 of the blow gas are branched off, and in

order to bring about the removal of coke by the action of the draught, said out-let channels have in accordance with the present invention a determined form. For obtaining the result aimed at it is essential, that the 60 edge formed by the bottom of the channels and of the mantle of the generator lies in the plane of the natural slope of the coke or only slightly outside of this plane. The bottom of the channel must be slanting in 65 order to allow the coke arriving at the orifice of the channel to slide on and furthermore from this channel another channel or receiver must be branched off in which the coke is collected.

Further features of the invention will be 70 set out with reference to the drawing which, by way of example, illustrates a generator for producing mixed gas, constructed and working in accordance with the invention. 75 In the sectional elevation showing the generator the distillation chamber is designated by 1 and the gasifying chamber by 2. The diameter of the latter is larger than that of the distillation chamber, so that the coke 80 sinking down from the distillation chamber forms a slope at the junction of said two chambers. The slope 3 confines together with the mantle and the top of the gasifying chamber the channel 4. From the latter the 85 transversal channels 5 are branched off, which during the blowing period allow the escape of the blow gases. These gases may for instance pass thereafter around the chamber 1 and then escape through the flue 90 6. From the channel 5 a receiver 14 is branched off the bottom 15 of which is detachable. The bottom of the channels 5 is slanting outwardly and arranged in such 95 manner that the edge 7 formed by the bottom of the channel and the mantle of the lower part of the generator lies in the plane of the slope 3 or only slightly outside of it. 8 is a flap, which may be turned from outside, for instance by means of the handle 9 and can 100 be fixed in any position. In the position as shown on the left-hand side of the drawing this flap is lying in the plane of the bottom of the channel and therefore does not constitute a hindrance to the coke sliding down the 105 bottom of the channel. When fixed in the upright position (right-hand side of the drawing) this flap 8 will obstruct the sliding movement of the coke until the material amassed on the bottom of the channel will 110

- have reached the height of the upper edge of the flap. 10 is a bracket extending into the distillation chamber for the purpose of causing the coke to break into pieces when 5 arriving at its edge. For the same purpose a roller 11 may be employed which on its periphery is provided with rails working as breaking means. By a gear 12 having a click and ratchet wheel the roller is rotated 10 at a slow speed.
- The generator works as follows: The air blown in at 13 passes through the incandescent coke contained in the gasifying chamber whereby blow gas is produced, which is 15 collected by the channel 4 and escapes through the transversal channels 5. The speed of the draught will be the highest at the point where the gases are passing over from the channel 4 into the channel 5. In 20 this place the pieces of coke lying in the slope will be swept by a vigorous stream of gas whereby they are brought to slide down along the bottom of the channel directly into the receiver 14, provided that the flap 25 8 is in its position as shown on the left-hand side of the drawing. This sliding down movement of the coke will during the period of the blowing go on until the receiver 14 will be filled and the slope of the 30 coke amassed within the channel and the receiver will acquire the direction as indicated by the dot and dash line A—B. If the coke has settled up to this slope, the draught will not be able any more of causing further material to slide down. If a further 35 removal of coke is desired, the receiver has to be evacuated by opening its bottom 15, whereafter the described procedure will set in again.
- If the generated coke is caked together it has to be broken when passing from the channel 4 to the channel 5 and according to the degree of the caking either the bracket 10 may be sufficient which, when the caked 40 mass is pressed against its edge will crumble it, or else the breaking roller 11 has to be employed. From the coke sinking down from the distillation chamber in the form of a more or less solid or coherent column, 45 the rails of the roller will break off pieces, which are adapted of settling with the natural slope. Furthermore in the upper port of the outer wall of the receiver an opening 20 may be provided which is normally closed and through which some tool 50 may be introduced for breaking up the coke.
- The inclination of the natural slope depends upon the qualities of the coke and consequently may vary in accordance with 55 changes of the material. It therefore may happen that the edge 7 determining the support of the material may be situated too deep, in which case more coke should be removed as is desirable, or else too high, in 60 which latter case the said edge would im-
- pede the removal by the action of the draught. To such changes of the qualities of the material the apparatus can be accommodated by altering the position of the flap 8 accordingly. If the friction co-factor 70 is too high, the flap is laid down and kept in the position as shown on the left-hand side of the drawing. If on the other hand the said friction coefficient is a small one, the flap has to be turned up to the appropriate height, so that its edge 16 will lie within the plane of the slope formed by the coke when left to itself, or only slightly outside thereof. 75
- The operation of the generator itself is known. The air is blown in at 13, carries the blow gases with it through the channels 5 into the space surrounding the retort and then escapes into the chimney 6. When the blowing is stopped, the valves 17 are closed 80 and steam is admitted at 18, into the gasifying chamber containing the incandescent column of coke. The generated gas passes through the coal contained in the distillation chamber and then escapes through the 85 outlet 19.
- What I claim is:
1. In a combined coking retort and gas generator comprising an enlarged lower part and transversal channels branching off from the junction of the upper and the lower part and constituting the out-let for the blow gases the inclination of the bottom of these channels slanting outwardly and the disposition of the bottom edge of the channels 90 orifice at such height, that it lies approximately in the plane of the slope naturally formed by the coked material when settling in front of the orifice. 95
  2. A combined coking retort and gas generator comprising an enlarged lower part, transversal channels for the escape of the blow gases branched off from the junction of the upper and lower part with a bottom slanting outwardly, the edge of which 100 bottom at the orifice of the channel lies in the plane of the natural slope of the coke, and a receiver branched off from the transversal channels. 110
  3. A combined coking retort and gas generator comprising an enlarged lower part, transversal channels for the escape of the blow gases branched off from the junction of the upper and lower part with a bottom slanting outwardly, the edge of which 115 bottom at the orifice of the channel lies in the plane of the natural slope of the coke, and means for breaking up the coked material at the entry from the upper part into the lower part. 120
  4. A combined coking retort and gas generator comprising an enlarged lower part, transversal channels for the escape of the blow gases branched off from the junction of the upper and lower part with a bottom 130

slanting outwardly, the edge of which bottom at the orifice of the channel lies in the plane of the natural slope of the coke and a breaking roller for breaking up the coked material at the entry from the upper part into the lower part.

5. A combined coking retort and gas generator comprising an enlarged lower part, transversal channels for the escape of the 10 blow gases branched off from the junction of the upper and lower part with a bottom slanting outwardly, the edge of which bottom at the orifice of the channel lies in the plane of the natural slope of the coke, a flap 15 journalled to the bottom of the channel in its plane, the position of which flap is adjustable, and means for fixing the flap in any position.

6. A combined coking retort and gas generator comprising an enlarged lower part, 20 transversal channels for the escape of the blow gases branched off from the junction of the upper and lower part with a bottom slanting outwardly, the edge of which bottom at the orifice of the channel lies in the 25 plane of the natural slope of the coke, a flap journalled to the bottom of the channel in its plane, the position of which flap is adjustable means for fixing the flap in any position and means for breaking up the coked material at the entry from the upper part of the generator into the lower part.

In testimony whereof I have affixed my signature.

ALBERT BREISIG.
